UNITED STATES PATENT OFFICE.

ANGELO BRUGILA, OF NEW YORK, N. Y.

CIGARETTE-BOX.

1,175,336.

Specification of Letters Patent. Patented Mar. 14, 1916.

Application filed April 2, 1915. Serial No. 18,806.

To all whom it may concern:

Be it known that I, ANGELO BRUGILA, citizen of the United States, residing at 611 West Two Hundred and Fourth street, 5 New York, in the county of New York and State of New York, have invented certain new and useful Improvements in Cigarette Boxes, of which the following is a specification.

10 This invention relates to cigarette boxes and more particularly to the class of cigarette boxes which have contained therein a plurality of matches for the convenience of the person using the cigarette.

15 The primary object of the invention is the provision of a cigarette box which will have the matches hinged to one of its edges and connected to the cover in such a manner as to bring the matches into convenient 20 reach of the user when the box is opened.

With these and other objects in view which will appear as the description progresses the invention resides in the novel features of construction, simplicity and 25 cheapness to manufacture.

In the drawings—Figure 1 is a perspective view of the cigarette box shown in open position, Fig. 2 is a vertical cross sectional view of the box shown in open position, 30 Fig. 3 is a vertical cross sectional view of the box shown in closed position.

Referring now to the drawings in which like characters of reference designate similar parts throughout the several views the 35 numeral 1 indicates the container in which the cigarettes are held. The container 1 is constructed in accordance with the usual method of constructing cigarette boxes and has hinged to one side thereof as at 2 a cover 40 3 which is adapted to fit over the container 1 in a neat and snug manner as shown clearly in Fig. 3.

Affixed to the inside of the container, on the side upon which the cover is hinged, is a 5 sheet of paper 4 which is secured by glue or paste to the side of the box as at 5. A row of matches 6 of the kind ordinarily arranged in strips, is mounted upon the sheet

of paper 4 at a point slightly above the edge of the container 1 and these matches 50 are glued or cemented to the paper at their lower marginal edge. Another sheet of paper 7 is pasted in the inside of the cover for about half the area of the cover from which point it is brought over to the lower 55 marginal edge of the strip of matches and glued or cemented thereto as shown at 8.

By referring to Fig. 3 it will be observed that when the cover 3 is closed upon the container the sheet of paper 4 lies flat against the cigarettes and the matches lie on this paper and the sheet of paper 7 is folded upon itself as at 9 thereby making a neat and compact whole. Now when the cover is raised for the purpose of obtaining a cigarette the sheet of paper 7 will act as a pull strip or tug and raise the matches to a vertical position as shown in Fig. 2 where they will be within convenient reach of the user and the strip of paper 4 which is interposed 70 between the matches and the cigarettes will also raise and expose the cigarette so that they may be readily removed after which a match may be broken off the row 6 and struck upon the prepared surface 10 at the 75 side of the box to light the cigarette.

I claim:

A cigarette box having a cover hingedly connected thereto, a sheet of paper fixedly connected at its lower end to the interior side 80 of the rear wall of the box, the free portion thereof being offset into parallelism with the secured end when the cover is open, a match strip secured to the paper sheet and adjacent the fixed end and positioned so 85 that the lower edge of the strip will be flush with the upper edge of the box when in a vertical position, and a paper sheet secured to the upper portion of the cover and to the lower extremity of the match strip. 90

In testimony whereof I affix my signature in presence of two witnesses.

ANGELO BRUGILA.

Witnesses:

CHARLES FRAUNDORF, Jr.,
VAN VINCENT.
